UNITED STATES PATENT OFFICE.

CHARLES W. SAALBURG, OF RICHMOND HILL, NEW YORK, ASSIGNOR TO MULTICOLOR INTAGLIO PRESS COMPANY, OF NEW YORK, N. Y., A CORPORATION OF DELAWARE.

METHOD OF PRODUCING ETCHED INTAGLIO PRINTING-SURFACES.

1,290,786.

Specification of Letters Patent.

Patented Jan. 7, 1919.

Application filed February 27, 1917. Serial No. 151,169.

To all whom it may concern:

Be it known that I, CHARLES W. SAALBURG, a citizen of the United States, residing at Richmond Hill, in the county of 5 Queens and State of New York, have invented certain new and useful Improvements in Methods of Producing Etched Intaglio Printing-Surfaces, of which the following is a specification.

10 This invention is in part a method of producing an etched intaglio printing surface of a novel and improved character on an etchable roll or plate. One object of the invention is to produce a durable etched printing surface and also to obtain fine gradations of light and shade correspondent to the gradations of light and shade in the subject-matter picture to be reproduced by use of 15 photographically - sensitized carbon - tissue prints in a multicolor press printing operation.

Another object of the invention is to produce a novel and durable printing surface of the kind in question,—that is, of a combined 20 half-tone and grain-screen print structure. And another object is to produce a novel kind of press-printed etching having a plurality of colors some of which are superimposed, such print or etching being characterized by a combined half-tone and grain-screen coloration.

In the accompanying drawings forming a part hereof and illustrating the principle of this invention in the best mode now known 25 to me,—

Figure 1 is a face view of a half-tone positive.

Fig. 2 is a negative photographically-sensitized carbon-tissue or film print of the half-tone positive shown in Fig. 1.

Fig. 3 is a perspective view of an etchable roll, and shows the print which is shown in Fig. 2, transferred to and dried on the periphery of the roll.

Fig. 4 is a face view of a grain-screen photographically-sensitized carbon-tissue or film print.

Fig. 5 shows the grain screen film print shown in Fig. 4, transferred to and dried on the half-tone print film which is in place on the surface to be etched.

Referring to the drawings, the said half-tone positive is indicated by 1 on any suit-

able transparent material. It shows as numerous dots 2 of various sizes, these dots 55 showing in black in the drawings and defining the tones of the picture. This half-tone positive I use for the purposes of the present method in assemblage with a sheet of photographically-sensitized carbon tissue or film to make the half-tone negative print 3 shown in Fig. 2, wherein the black dots 3 are the reverse of the black dots 2 shown in the positive 1. The black dots 3 in the negative film form a 60 resist for the etching acid and consequently protect the underlying metal of an etchable surface from being attacked by the acid, and accordingly effect the formation of the solid walls of the ink-holding recesses or pits in 65 the etched surface; the white spaces 4 of the negative, between the dots 3, constituting film portions which are bitten through by the etching acid so that the acid eats through 70 the etchable metal to form the ink-holding recesses or pits. Not only is there undercutting, but also eating away of the top surfaces of the walls when the half-tone dots are so small that the underlying metal is of 75 minute area.

Now I find that I can overcome this serious objection and keep all the tones of the picture by superimposing a separate photographically-sensitized carbon tissue or film grain-screen print 6 of minute black grains 80 or dots 7, the grain-screen black dots 7 being preferably near the size of the black dots of the negative. These black dots or grain 7 of the grain screen are acid resists and serve to enlarge the walls of the ink-holding recesses finally formed in the parts of the metal where the thinnest walls would appear if the etching were made directly through the half-tone negative; and the combination of the half-tone and grain serves to 85 give to the etching in the metal and the print made therefrom, a peculiarly harmonious and full tone picture of a wholly distinctive character.

In Fig. 3 I show the half-tone film negative print transferred to and dried on an etchable roll 5. Now the fact is that if the etching acid be applied directly to this negative the acid will undercut the walls of the cells and eat away in whole or in part such 90 walls, destroying the thinner walls first, es-

pecially in the blacks and three-quarter tones,—when and if the half-tone screen used is say from 85 to 175 lines to the inch, and it is this screen size which is required 5 in multicolor or monotone etched intaglio printing; and it is assumed a screen of from 85 to 175 lines to the inch is used in the making of the negative tissue print. But whatever the number of screen lines per inch, the 10 law of the matter is that the finer the screen the greater the liability to undercut the ink-recess walls.

Said grain screen print is indicated by 6. This grain-screen tissue or film print is 15 transferred to and dried on the already dried half-tone negative print, making a double thickness of film through which to etch on the roll 5. The outer or grain screen tissue or film print constitutes a 20 screening or protective print in that it screens or protects the image to be reproduced in the underlying half-tone negative from mutilation in the etching process, tends to prevent devils; and as a screening or 25 protective print in connection with other kinds of film prints and other kinds of screens, effects important novel advantages. My invention is not limited in respect to the prevention of devils to either the half-tone 30 negatives or to grain-screen prints referred to above, and the broad advantages of my duplex film method are as follows. The outer screening of protective film or tissue covers pinholes and blemishes in the underlying 35 image-containing film print and prevents the acid from penetrating such pinholes and blemishes, and obliterates devils arising from dust specks on the films, and prevents the acid from improperly attaching 40 the copper through them. Any such biting into the copper or etchable surface would produce ink-receiving recesses or cells where such recesses were not wanted, and would result in blemishing the surface of 45 the printed product. The pinholes, blemishes or devils are due to a variety of causes such as accidental perforations or bruises, to imperfections in manufacture, to dust specks, and to a considerable extent to inherent 50 action during warm weather or under wrong temperature and hygrometric conditions. In very warm weather or under otherwise adverse conditions, the devils and blemishes are particularly liable to be seen 55 in large light-colored areas such as skies or flesh masses or the like, where the resultant imperfections are particularly objectionable. The screening or protective print if it has imperfections, can hardly be possibly placed 60 on the underlying film print so that its entire imperfections will register with minute imperfections in the underlying print. While image-containing films are often printed with screens in glazed frames by exposure 65 to light, such an etchable medium

is a single thing. In such case the dots, stippling, or the like of the images of the subject-matter and of the screen lines are in the single film; and in applying the etching acid to such a film when it is in place on an etchable surface, there is no adequate time and opportunity afforded to the etcher for the determination of the quality of his etching as the etching proceeds, and very often the etching under such conditions has to be 75 stopped before completion, by reason of such imperfections. In such case the etcher has no recourse except to start his work over again or to produce an undesirable etched printing surface. By my invention 80 of the duplex films as stated, because the subject-matter image to be reproduced is underneath the screening or protective tissue print or film and protected thereby, the etcher has much more time and opportunity 85 for observation of the effects of the acid and of the quality of the etching which is being made and can modify, vary and regulate the operation of the etching acid and so control the depth of its penetration into the copper, 90 and this he can do with greater certainty and facility than he can with the single tissue or film print referred to. In the latter case it is very difficult to etch deep and sharply 95 into the copper and thereby produce deep and sharp ink-holding recesses which are often desirable not only for obtainment of desired effects on paper and fabrics generally, but also in the printing of some classes 100 of textile fabrics for forcing the ink clear through the goods and so securing the required printed appearance of some classes of goods on the so-called wrong side thereof. There is a most important physical effect 105 produced by the described duplex process, and it lies in the fact that the screening print, while resulting in the two marked advantages above stated, does not permit, but prevents, mutilation of the image embodied 110 in the under tissue or film. The outer print is bitten through without the acid reaching the image-containing portion of the composite or duplex film structure; whereas, if the positions of the two films were reversed, then the acid would operate in the image-containing film which would be outermost 115 and bite it variously before coming to the under film with its dot or stipple or other shade-forming images, and the resultant etching would be blurry where by the present process it is strong, sharp and clear. 120 Whether the positive and the carbon-tissue or film print of the positive are half-tone or not, and whether the screen print is a grain screen print or not, the duplex film process described possesses a peculiar advantage which in some classes of work is particularly intensified by using the described half-tone positive half-tone film print and grain screen print in producing 125 130

etched printing surfaces and superimposed color etchings which are strikingly correspondent in art values to the art values or other characteristics of original paintings, 5 watercolors, pastels, chromos, or other color pictures; and in the process of reproducing the color values and characteristics of such color originals, I may employ photographic color-separation processes or the like. In 10 any event the etched printing surface and the printed etching in multicolor possess striking increased sharpness and degrees of tone shades. The acid bites through the unexposed white dots or equivalents of the 15 protective screen print first, and consequently the thinnest parts of the underlying image-containing film are attacked before its other parts are attacked, and then the acid spreads and bites on and into the underlying image-containing film according 20 to the varying thicknesses thereof. It will be understood that each of the films has its usual paper back stripped off. The screening or protective print being outermost, insures 25 the production of all the shades or shading in the negative film by reason of the latter being fortified by the outward protecting screen.

In addition to its utility as a screening 30 or protective film print, the print which contains the image to be reproduced in etching the printing surface and subsequently to be reproduced on the product which is press-printed from the etched roll when combined, 35 with an overlying fine grain screen, is of great practical importance in the following important particulars: The grain of the grain screen which, according to the present invention, is also a screening or protective 40 screen as above referred to, effects marked strength and durability of the tooth of the metal etching,—that is of the metal surrounding the ink-holding cavities, cells, or pits made in the surface of the roll or of a 45 plate by the etching acid; and this durability of tooth is of very great importance, first in prolonging the life of the tooth under the action of the doctor blade of the press and the general wear due to its use in 50 making printed impressions, and secondly by the maintenance of the tooth in securing a non-blurred printing effect especially in the printing of long editions where a blurring effect obtains as soon as the tooth of a 55 plate wears. Of course the finer tooth wears down more quickly than the coarser tooth, and as the fine tooth corresponds to the darker shaded spaces of intaglio printed products any wearing down of these finer 60 teeth results in a blurred black or other color or in other more or less blurred or solid ink surfaces in the product where only a fine shading of the color is desired. By 65 the grain screen feature of the present invention the grain effected by the grain

screen of uniform sized dots, fills in or covers the portions of the underlying negative half-tone film where the dots are very fine and would etch away or be liable to be etched away if they were not protected by the 70 screen or protective fine screen print unless great care were exercised by the etcher in the application of the acid, as occurs in the etching of ordinary half-tone positive films. 75

Such covering or filling in of the half-tone negative with its dots of varying sizes by a fine screen film or tissue print which forms an overlying screening or protective screening print having dots of substantially 80 uniform size and closely assembled together prevents the acid from attacking the finer dots of the half-tone and insures a durable tooth in the etched printing surface, and also a sharply defined intaglio printed product. 85

The importance of this invention in connection with the half-tone positive, the negative film print made therefrom, and the grain screen print method, may be further 90 explained as follows. A half-tone picture is composed of small dots of varying sizes but of equal density in respect to color, and that is a characteristic of the half-tone positive shown in Fig. 1, and of the half-tone positive film print shown in Fig. 2. When such a half-tone positive film print is acidized by itself, the result is that when the dots are very small, particularly in solid blacks and three-quarter tints, the acid after a short 100 etching operation eats the metal away so that there is no adequate well formed for the ink, and the ultimate result is that the paper on which the press printing is done becomes smudged. Therefore in order to 105 prevent such a smudge I use the protective film print 6 comprising a series of fine grain dots which automatically under the etching action of the acid will produce proper ink-receiving wells in the dots, giving the wells 110 or pits suitable mechanical strength for practical use in press printing. The grain film where the grain does not exist forms a protection for the underlying half-tone small dots, and this outward grain film 115 effects a toothing of the metal which toothing would be greatly impaired or destroyed if it were accomplished by use of the half-tone positive film alone. The exterior or outer grain screen print or other screen 120 print affords a protection to the underlying negative film print whether it is half-tone or not, because the acid biting into the spaces between the resistant portions of the outer screen when free, and eating in every direction, would destroy the under structure of the positive film print. But whether the under film print 3 is a half-tone or a flowing gelatin print, the superimposed outer screen print advantageously affects the mechanical 125 130

structure of the etching on the printing member, and enhances the beauty of the ultimate multicolor intaglio print.

What I claim is,—

- 5 1. The process of avoiding devils consisting in transferring to an etchable roll or plate a carbon negative print film containing the image of subject-matter to be reproduced and drying such film on the etch-
10 able surface; and in thereafter transferring to and drying on such image-containing film, a sensitized carbon-tissue screening film print; and in subjecting the superim-
15 posed films and such parts of the etchable roll or plate as are to be etched, to a suitable etching acid.
2. The method of making etched printing rolls or surfaces for printing, consisting in transferring a photographically-sensitized
20 carbon-tissue print of a subject-matter image to be reproduced and made from an isochromatic negative to an etchable surface; in drying such print in place on such surface; in transferring to such dried
25 image-containing print a photographically-

sensitized carbon-tissue print of screen, dot, stipple or other shading character and drying such protecting or screening print thereon; and in applying to such film assem-
blage an etching acid.

3. The method of making modified half-tone etchings on an etchable surface to be used in printing, consisting in transferring a photographically-sensitized carbon-tissue half-tone negative print to said surface and allowing it to dry in place; in superimposing over such dried negative print a photographically-sensitized carbon-tissue grain-screen print and allowing it to dry on the underlying half-tone negative tissue print; and in acid-etching through such superimposed tissue prints.

4. As a new article of manufacture, a superimposed-color, multi-color etched print, the coloration whereof comprises combined half-tone and grain screen coloration im-
pressions.

In testimony whereof I have hereunto set my hand this 24th day of February, 1917.

CHARLES W. SAALBURG.
